United States Patent Office

Des. 205,941
Patented Oct. 11, 1966

205,941

PANTY GIRDLE OR SIMILAR ARTICLE

Olga Erteszek, Los Angeles, Calif., assignor to Olga Company, Van Nuys, Calif., a corporation of California

Filed Feb. 7, 1966, Ser. No. 934

Term of patent 14 years

(Cl. D20—2)

FIG. 1.

FIG. 2.

FIG. 1 is a front perspective view of a panty girdle showing my new design; and

FIG. 2 is a rear view thereof.

The essential features of my design reside in the zigzag stitch pattern shown within the full line disclosure on the drawing.

I claim:

The ornamental design for a panty girdle or similar article substantially as shown and described.
